CLAIM

The ornamental design for a lamp fixture, as shown and described.

DESCRIPTION

FIG. 1 is a perspective elevational view of a lamp fixture and showing the front, left side, and top thereof according to the present invention;

FIG. 2 is a front elevation view of the lamp fixture shown in FIG. 1;

FIG. 3 is a right side elevation view of the lamp fixture shown in FIG. 1, the left side elevation view being a mirror image thereof;

FIG. 4 is a bottom plan view of the lamp fixture shown in FIG. 1;

FIG. 5 is a top plan view of the lamp fixture shown in FIG. 1.

FIG. 1

FIG. 2

FIG. 3

FIG. 4

FIG. 5
